HAIR-SLIDE

The present invention relates to a hair-slide.

Known slides of this kind include a base, a clasp and a curved spring blade the ends of which rest on the base and which will be termed "spring" hereinafter. The spring must be slid by hand underneath other parts, involving a nonnegligible amount of time in mass production. In a hair-slide according to this invention, the spring is hinged on the base, thus enabling it to be fitted much more quickly. Further, the parts making up the hair-slide can have unusually simple shapes. The description which follows with reference to the accompanying nonlimitative exemplary drawing will give a clear understanding of how the invention can be carried into practice.

IN THE DRAWING

FIG. 1 shows a flat element which following bending and curving forms the base of a hair-slide;

FIG. 2 shows a flat element which subsequent to curving forms the clasp of the hair-slide;

FIG. 3 shows a flat element which following bending and curving forms the spring of the hair-slide;

FIGS. 4, 5 and 6 are diametrical longitudinal sectional views of the hair-slide in its open position, in its closed position when it does not grip the hair, and in its closed position when it grips the hair, respectively.

The hair-slide described hereinbelow in symmetrical in relation to a longitudinal plane. For greater clarity, identical parts which are symmetrical in relation to said plane will be designated by like reference numerals.

The three flat elements in FIGS. 1, 2 and 3 are cut from a sheet of metal, for example a sheet of carbon steel, and the parts obtained after they have been deformed as defined above are hardened prior to assembly. These parts will be designated hereinafter by the same reference numerals as the corresponding flat starting elements. The flat element 10 shown in FIG. 1 includes a rectangular strip 11, two tabs 12 perpendicular to strip 11 adjacent one end thereof, each being formed with a hole 13 adjacent one end thereof, and two other tabs 14 likewise perpendicular to strip 11 and positioned adjacent the other end thereof and each formed with hole 15 therein. The tabs 12 and the tabs 14 are subsequently bent at right angles to strip 11 in order to respectively form the bearings for first and second hinge-pins.

The element 16 shown in FIG. 2 is generally strip-shaped with stubs 19 adjacent one of its two ends, is rounded at its other end 20, and is formed with a long opening 18 formed along the greater part of its length and the ends of which are designated 18a and 18b. The two stubs 19 are intended to engage into the holes 15 of bent tabs 14 and to thereby form a hinge-pin for clasp 16 in relation to base 10.

The element 21 shown in FIG. 3 comprises a long strip-shaped central portion 22 terminating at one end 22a in a wider portion 23 and at its other end 22b in a wider portion 24. This wider portion 24 is formed laterally with two stubs 25 intended to engage into the holes 13 of bent tabs 12 and to thereby form the hinge-pin for spring 21. Widened portion 24 is formed with an opening 26 therein bounded adjacent the end of the element by a transverse edge 27 and having two inwardly jutting transverse protrusions 29 which, alternatively, may meet to form a single transverse portion.

The widened portion 24 includes a first part 30 of transverse width not exceeding the width of strip 11 and, at the end of the element, a second part 31 wider than strip 11.

The portion of element 21 enclosing the second opening 28 is shaped as a two-pronged fork having its handle formed by the central part 22 of the element, and the transverse linear section of the two straight parallel parts of the two fork prongs 34 is greater than the transverse linear section of the central part 22 of element 21.

The hair-slide is made as follows:

The strip 11 is curved slightly to give it the shape shown in FIGS. 4, 5 and 6. The element 16 is curved slightly to make it

2

substantially parallel to strip 11, as shown in FIG. 5. The flat element 21 is deformed into the shape shown in FIGS. 4 and 5. These three parts are then hardened and the stubs 19 are inserted into the holes 15 in the bent tabs 14 and the stubs 25 into the holes 13 in bent tabs 12. This completes manufacture of the hair-slide.

As shown in FIGS. 4 and 5, the central portion 22 of spring 21 is arched above strip 11 of base 10, while the widened portion 24 of spring 21 includes the hinge-pin 25 of spring 21 and is curved in the opposite direction to central portion 22, and the portion 23 of the spring adjacent the free end thereof is located between strip 11 of base 10 and the hinge stubs 19 of clasp 16.

From what has been said hereinbefore concerning the transverse widths of the two portions 30 and 31, it follows that the first portion 30, from which project the stubs 25 forming the hinge-pin of spring 21, is capable of pivotal motion between the lateral bearings of said hinge-pin, formed by the bent tabs 12, and that pivotal motion of the second part 31, which is wider than part 30, in an anticlockwise direction (when viewing FIGS. 4 to 6), i.e. in the direction tending to move the central portion 22 of spring 21 nearer to strip 11, is arrested by the bent tabs 12.

In order to obtain the closed position shown in FIG. 5 from the open position shown in FIG. 4, the clasp 16 is first applied on the edge 24, then pressed. This increases its curvature, thus reducing the linear distance between its ends; further, under the effect of the pressure exerted on edge 27, the portion 31 rotates slightly, causing the end 20 of clasp 16 to pass beneath the edge 27, as shown in FIG. 5. At the same time clasp 16 may bear at 18b against spring 21, thus subjecting the latter to a rotating moment about its hinge-pin 25 and consequently causing its free end to bear against strip 11 at 23. Clasp 16 may alternatively not bear against spring 21, in which case its rotation will be arrested by the protrusions 29.

To open clasp 16 pressure is exerted on the part 31 of the widened portion 24 of spring 21. This part 31 is located externally of hinge-pin 25, so that widened portion 24 pivots in a clockwise direction (as seen on the drawing), thus disengaging the edge 20 of the clasp from the edge 27 of external part 31. Spring 21 continues to pivot about its hinge 25 and its end portion 23 adjacent the hinge-pin 19 of clasp 16 therefore comes to bear at 22a against the inside face of clasp 16 and thus causes the latter to rotate anticlockwise about its hinge-pin 19, i.e. in the direction in which it opens.

In FIG. 6, the hair (not shown) gripped by the hair-slide is held between clasp 16 and spring 21. As FIG. 6 shows, its pressure has caused spring 21 to pivot about its hinge-pin 25, and the free rounded end 20 of clasp 16 has advanced further beneath the edge 27 of part 31, thus increasing the clamping force of clasp 16. The external part 31 of the widened portion 24 of spring 21 has been arrested by the bent tabs 12. This widened portion 24 offers greater resistance to deformation than the central spring portion 22 because, as stated previously, its transverse linear section is greater than the transverse linear section of the central spring portion 22. The central spring portion 22 cannot therefore move too far away from clasp 16, so that the hair remains securely clasped by the hair-slide.

When clasp 16 is opened by pressing the part 31, the hair gripped between it and the central portion 22 of spring 21 in this case resists the rotation of spring 21 about its hinge-pin 25. However, the widened portion 24 of spring 21 possesses considerable elasticity due to the opening formed therein, as a result of which widened portion 24 is caused to pivot clockwise about hinge-pin 25 and thereby disengage the free end 20 of clasp 16 from transverse edge 27. In this case the pressure exerted by the hair helps to open clasp 16.

I claim:

1. A hair-slide which includes a base comprising a strip portion, a spring pivoting in relation to said base about a transverse hinge located adjacent one end of said base and which has a central arched portion above said strip, a flexible clasp

pivoting in relation to said base about a second transverse hinge located adjacent the other end of said base and which is formed with a long opening along its length into which penetrates said central spring portion when said clasp is in its closed position, the free end of said clasp, when it is in its closed position, being held in place, in the absence of a pressure exerted on the spring, by a portion of said spring.

2. A hair-slide according to claim 1 wherein said spring is formed adjacent its hinge with a widened portion formed with an opening therein located externally of this hinge, and wherein that portion of said spring which is located externally of said opening forms said spring portion which holds said clasp in its closed position.

3. A hair-slide according to claim 2 wherein said widened portion comprises the hinge of said spring and is curved oppositely to the central portion of said spring.

4. A hair-slide according to claim 2 wherein said widened portion includes a first part from which stems said spring hinge moving between the lateral bearings thereof, and externally of said first part, a second wider part of which the pivotal motion which moves said central spring portion towards said base is arrested by said lateral bearings.

5. A hair-slide according to claim 1 wherein said spring is formed adjacent its hinge with a widened portion formed with an opening therein located externally of this hinge, said widened portion being formed with two transverse protrusions projecting into said opening, and wherein that portion of said spring which is located externally of said opening forms said spring portion which holds said clasp in its closed position.

6. A hair-slide according to claim 1 wherein said spring is formed adjacent its hinge with a widened portion formed with an opening therein located externally of this hinge, and wherein that portion of said spring which is located externally of said opening is shaped as a two-pronged fork the handle portion of which is formed by said central spring portion.

7. A hair-slide according to claim 6 wherein the sum of the 15 transverse linear sections of the parallel portions of the two fork prongs is greater than the transverse linear section of said central spring portion.

8. A hair-slide according to claim 1 wherein that portion of the spring which is adjacent the free end thereof is located 20 between the strip portion of said base and the hinge axis of said clasp.
